UNITED STATES PATENT OFFICE.

ELLSWORTH F. BULLARD, OF HACKENSACK, NEW JERSEY.

DESIGN FOR ORNAMENTED PAPER.

SPECIFICATION forming part of Design No. 34,463, dated April 30, 1901.

Application filed March 28, 1901. Serial No. 53,369. Term of patent 14 years.

To all whom it may concern:

Be it known that I, ELLSWORTH F. BULLARD, a citizen of the United States, residing at Hackensack, county of Bergen, State of New Jersey, have invented and produced a certain new and original Design for Ornamented Paper, fully described and represented in the following specification and the accompanying drawing, forming a part of the same.

10 The design is intended to be placed upon or worked into paper, such as safety-paper.

The leading feature of the design comprises the angularly - arranged lines 1 and 2, the curved lines 3 and 4, crossing one of said an-

gularly-arranged lines, and the curved lines 15 5 and 6, said device being repeated over the paper.

What I claim is—

The design for ornamented paper substantially as shown and described.

In testimony whereof I have hereunto set my hand, this 27th day of March, 1901, in the presence of two subscribing witnesses.

ELLSWORTH F. BULLARD.
